ATTORNEY.

UNITED STATES PATENT OFFICE.

WILLIAM E. DAVIS, OF MORRISTOWN, NEW JERSEY.

FENCE.

1,095,459.

Specification of Letters Patent.

Patented May 5, 1914.

Application filed February 12, 1913. Serial No. 747,880.

To all whom it may concern:

Be it known that I, WILLIAM E. DAVIS, a citizen of the United States, residing at Morristown, in the county of Morris and State 5 of New Jersey, have invented certain new and useful Improvements in Fences; and I do hereby declare the following to be a full, clear, and exact description of the invention, such as will enable others skilled in the art 10 to which it appertains to make and use the same, reference being had to the accompanying drawing, and to figures of reference marked thereon, which form a part of this specification.

15 This invention relates to a fence which is made up of sections, the sections being adapted to be arranged end to end so as to build up a fence quickly and without undue labor, the fence sections being locked against longitudinal movement in relation to each other, and also being constructed to prevent lateral movement in relation to each other.

20 The invention consists of a fence of this type with sections having interlocking ends, each section being supported on one end by 25 a post and at its free end being supported on the supported end of the next adjacent section, the sections being constructed with a supported end adapted to engage the free 30 end of an adjacent section to lock the sections together.

25 The invention is further designed to provide a fence of this kind which can be used on level ground or which can also be used on 35 hillside and to go over inequalities in the ground in the shape of slight rises, or to be also fitted into depressions, the fence sections having a movement vertically in relation to their posts.

40 My invention consists further in a fence of this kind which permits the free end of a fence section to be fitted transversely to another section, either adjacent to its supported end or between braces at approximately 45 its center so that a partition fence can be attached to a line fence, either at right angles thereto or at an angle less than a right-angle, as will be understood.

45 The invention is illustrated in the accompanying drawing, in which—

Figure 1 is a side view of two fence sections connected. Fig. 2 is an enlarged end view of the supported end of a section. Fig. 3 is a perspective view of a section, and Fig. 55 4 is a reduced plan showing the manner of attaching transverse sections, for instance

the attachment of partition fences to line fences.

Each fence section is supported at one end and its other end is free, the free end being 60 adapted to be lowered into the supported end of the adjacent section and thus support it against downward movement, transverse movement or longitudinal movement. Each section consists of a post, the post being 65 adapted to be made in different forms, but I prefer to make it of the studs 10, the braces 11, which are on the outside of the studs, and the shelf 12, the shelf 12 having grooves 13 to receive the bottom ends of the studs 10. 70 The studs are preferably arranged out of line transversely so as to provide a space 14 between them, this space being illustrated in Fig. 1. Secured by pins 15 to the studs 10 are the rails 16, the rails forming a body 75 portion and being held apart by braces 17, the braces also being arranged out of line transversely to provide the space 18 between them for purposes to be hereinafter described. The braces are secured to the rails 80 by suitable bolts or pins 19. The free ends of the rails 16 are held apart by a strip 20 fastened to the rails by bolts or pins 21. Near their supported ends the rails are recessed on their top edges at 22, leaving the 85 end 23, which end 23 can be fitted into the free end of the next adjacent section, since the free end of each section is recessed on its lower side as at 24, the recesses 24 receiving the ends 23, and the ends 25 being adapted 90 to rest in the recesses 22. The braces 11 are fastened to the studs 10 by the pins or bolts 26, and to the shelf 12 by the bolts 27.

When a section is to be attached to an adjacent section all that it is necessary to 95 do is to lift the free ends and then lower them into the supported ends of the rails of the next section. The hooked ends, which are formed by means of the recesses, prevent the longitudinal separation of the 100 rails of one section from the rails of the next section, and transverse movement is prevented, since the free ends of the rails rest between the studs 10 of the supported end of the next section whereby they are 105 held against transverse movement and are kept aligned, although there is enough play to permit forcing a slight change of direction of one section as compared with an adjacent one. The connections or fastening 110 means between the rails and the studs and the braces and the strip are arranged so

that the pivotal connection is free enough to allow the free end of the section to be raised or lowered, but this pivotal connection is not free enough to permit a free swinging 5 of the section on its post, as this would result in a shaky or unstable fence, and the section when it is raised or lowered must be forced, but the pivotal connection, even if not freely movable, permits the raising of 10 the free end or a lowering thereof. A free end is shown raised in dotted outline in Fig. 1, showing the position the section would assume if that part of the fence was located at the foot of a hill. When the fence assumes 15 this position the movement at the post is slight, but when the free end of the fence is lowered or raised, one or the other of the studs 10 rises slightly in its groove 13, but the movement is so slight that the 20 pivots of the studs 10 are close enough together to keep the bottom ends of both studs in the grooves, although one or the other of them rises somewhat to accommodate 25 itself to the different inclinations of the fence section.

If a fence is to be used to form corners or a partition fence, the free ends of a right-angled section, such as at *a* in Fig. 4, can be fitted in a transverse position over 30 the rails 16 between the braces 17, being held against undue forward movement by reason of the strip 20 engaging the sides of the rails of the longitudinal section. In Fig. 4 at *b* I show a transverse section 35 which is so disposed that its free end rests

in the recesses 22, but in a transverse direction, the free ends being seated in the space 14 between the studs 10.

Having thus described my invention, what I claim is:—

A fence consisting of sections, each section comprising a post, the post consisting of studs, braces and a shelf, the shelf being slotted to receive the bottom edges of the studs, the braces being connected to the 40 studs and the shelf, rails pivotally connected to the studs so that the rails can be swung upward, braces secured to the rails and pivotally connected thereto, the braces being spaced apart to permit the transverse 45 passage of rails between them, the rails being recessed on their top edges adjacent to the studs and between the studs, the rails being recessed on their bottom edges near their free ends whereby the free ends of the 50 rails of the section are constructed to fit in the supported ends of the rails of a section, the recessed ends interlocking to prevent longitudinal movement of the sections from 55 each other, the studs preventing transverse 60 movement of the free ends of an adjacent section.

In testimony that I claim the foregoing, I have hereunto set my hand this eighth day of February 1913.

WILLIAM E. DAVIS.
